UNITED STATES PATENT OFFICE.

MARTIN NYSTROM, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

COMBINED PHONOGRAPH AND RADIO APPARATUS.

Application filed October 23, 1924 Serial No. 745,499.

This invention relates to an improved apparatus comprising a combination radio receiving set and a phonograph, and has for its primary object to provide novel means whereby a single amplifying horn may be employed with either the radio receiving set or the phonograph.

A still further object is to provide a valve having improved means which may be operated to direct the passage of sound from either the radio receiving set or the phonograph to the amplifying horn.

A still further object is to provide a valve of the above description so placed that it may be readily operated from the exterior of the cabinet in which the apparatus is placed.

A still further object is to provide new and simple operating means for a valve of the above description which may be readily applied to a variety of styles and sizes of apparatuses.

A still further object is to provide a valve having a passage therethrough which is adapted to form a portion of the passage from the phonograph or the radio receiving set to the horn, and which is so constructed that in either case the passage which the sound has to traverse will be smooth and continuous.

In the drawings in which I have shown preferred embodiments of my invention,

Fig. 1 is a front elevation of one form of apparatus embodying my invention.

Fig. 2 is a front elevation of a portion of my invention, detached from the remainder of the apparatus.

Fig. 3 is a plan view of the structure shown in Fig. 2, attached to an amplifying horn.

Fig. 4 is an elevation of the structure shown in Fig. 2 but taken from the opposite side to the view of Fig. 2, and showing the valve in a different position.

Fig. 5 is a section on the line 5—5 of Fig. 2.

Fig. 6 is a view corresponding to Fig. 1 but showing my invention embodied in a different type of cabinet and

Fig. 7 is a view corresponding to Fig. 2 of my invention as embodied in the cabinet shown in Fig. 6.

It is well-known that phonographs have been extremely popular and that that popularity is, in some instances, being supplanted by the popularity of radio apparatus. In other cases it is desired to possess both a phonograph and a radio apparatus. In any case the possession of both a phonograph and

a radio apparatus is somewhat expensive and furthermore these two apparatuses together take up a great deal of room. By my invention, however, I reduce the expense to a considerable extent by making use of the one amplifying horn with both the phonograph and the radio receiving set and thus also make possible the placing of both pieces of apparatus in one cabinet, thereby materially reducing the amount of space necessary.

Referring now to the drawings and particularly to Figs. 1 to 5 inclusive, the numeral 1 designates a cabinet of any suitable construction and having therein an amplifying horn 2. The cabinet further comprises the usual motor board 3, on which is mounted the phonograph turn-table 4, which is operated by any suitable mechanism. The cabinet 1 further contains a radio receiving set 5 of any suitable construction. In this embodiment, I have shown the receiving set as supported upon the motor board 3 and access to both phonograph and radio receiving set is had by lifting the covers 6.

Connected to the radio receiving set, by suitable means 7, is a loud speaker 8 and it is understood that the sounds received on the radio receiving sets are to be transmitted from the loud speaker 8 to the amplifying horn 2, as are also the sounds from the tone-arm 9 of the phonograph, which is mounted on the motor board.

Suspended on the under side of the motor board 3 is a valve preferably comprising a casing 10 in the general form of a Y, having the three legs 11, 12 and 13 which contain passages leading respectively to the tone-arm, loud speaker and amplifying horn. It will be seen that the leg 11 is provided with a flange 14 by which the valve may be secured to the under side of the motor board as by bolts or screws. The leg 12 receives one end of a neck 15 which is provided at its end 16 with a means to receive the loud speaker 8. In similar manner the leg 13 receives a neck 17 leading to the amplifying horn 2.

The casing 10 is provided with a cylindrical opening 18 in which is revolvably mounted a cylindrical valve member 19. The member 19 is provided with a curved passageway 20, which when the member 19 is in the position shown in Figs. 2 and 5, forms part of the passageway from the tone-arm 9 through the opening 3' in the motor board, and through the neck 17 to the horn. When the member 19

is rotated to the position shown in Fig. 4, the passageway 20 then forms a portion of the continuous passageway from the loud speaker 8, through the necks 15 and 17 to the horn.

Suitable means is provided for rotating the member 19 to bring the passageway 20 into either of the above described positions and this means is exemplified by a lug 21 preferably integral with the member 19 and carrying a screw 22 supporting a pinion 23 and a bracket 24. The pinion 23 is made fast to the lug by any suitable means 25, while the bracket 24 is loosely supported on the screw 22. The bracket 24 rotatably supports a hub 26 of a pinion 27, which is disposed at right angles to the pinion 23 and meshes therewith. Adjustably mounted in the hub 26 is an operating rod 28 which slides in the recess 29, wherein it is clamped in adjusted position by a set screw 30.

The operating rod 28 is provided with means to turn the same from the outside of the cabinet and in this instance such means consists of a knurled knob 31 connected to the operating rod 28 by a universal joint 32, providing means whereby the knob 31 may be placed at any desired location upon the outside wall of the cabinet. Suitable indicating means for showing the position of the valve is provided by a pointer 33 on the knob 31, which will co-operate with suitable legends upon the wall of the cabinet. These legends may, for example be "Phonograph" and "Radiola".

The movement of the valve member 19 is limited by a suitable stop 34, carried by the member and engaging a suitable member 35 upon the casing. The member 19 is held in place by the stop 34, which overhangs the edge of the opening and also by a screw 36, mounted on the other end of the member and engaging the other edge of the opening.

By this construction a simple turning movement of the knob 31 will serve to operate the valve so that the horn may be used with either the radio receiving set or the phonograph, the location of the valve being indicated by the pointer 33. It is of course understood that the valve may also be used to cut down the volume of sound coming either from the phonograph or radio receiving set, if such result is desired. In either position of the valve a smooth continuous passage will be provided for the full volume of sound coming through the horn and in making my valve in the form of a Y supported immediately underneath the motor board, I make it possible to reduce the cost of manufacture to a minimum, as substantially all that I require are two castings, the other parts being stock material.

Figs. 6 and 7 show my invention embodied in a different form of cabinet, the cabinet in this case being of the form wherein the horn 2 is directly under the phonograph tone-arm

9 and wherein the radio receiving apparatus 5' is placed directly under the horn. This form of cabinet has many advantages, in that it is more compact and because of the position of the radio receiving apparatus directly under the horn where it is placed in a drawer which may easily be pulled out. This arrangement is fully described and claimed in my co-pending application Serial #713,128, filed May 14, 1924. The mechanism employed with this form of cabinet is essentially, the same as that described above and includes a valve 10' and necks 15' and 17', the neck 17' being bent to connect with the horn which is, as pointed out above, under the phonograph.

I am aware that changes in the form, construction and arrangement of parts may be made without departing from the spirit and without sacrificing the advantages of the invention and I reserve the right to make all such changes as fairly fall within the scope of the following claims:

I claim:

1. In combination, a phonograph, a loud speaker, an amplifying horn, passageways from said horn to said phonograph and to said loud speaker, a rotary valve transversely disposed in and controlling both of said passageways, whereby sounds may be directed to said horn from either said phonograph or said loud speaker, a pinion on said valve, an operating rod, and a pinion on said rod and meshing with said first named pinion to rotate said valve. 100

2. In combination, a phonograph, a loud speaker, an amplifying horn, passageways from said horn to said phonograph and said loud speaker, a rotary valve controlling said passageways, a pinion on said valve, an operating rod, a pinion on said rod and meshing with said first named pinion to rotate said valve. 105

3. In combination, a phonograph, a loud speaker, an amplifying horn, a valve casing 110 having passageways communicating with said phonograph, said loud speaker and said amplifying horn, a valve in said casing and having a passageway therein, a pinion on said valve, an operating rod, and means on said 115 rod and engaging said gear for revolving said valve to bring said passageway into position to connect said amplifying horn with either said phonograph or said loud speaker passageways. 120

4. In combination, a phonograph, a loud speaker, an amplifying horn, a valve casing having three passageways communicating respectively to said phonograph, said loud speaker and said amplifying horn, a valve 125 in said casing and having a curved passageway therein, a pinion on said valve, a bracket loosely mounted on said valve, a pinion rotatably supported in said bracket and meshing with said first named pinion and means 130

connected to said last named pinion to revolve said curved valve to bring said passageway into position to connect said amplifying horn passageway with either said phonograph or said loud speaker passageways, and means to limit the rotation of said valve.

5. In combination, a phonograph, a loud speaker, an amplifying horn, a valve having three legs connected respectively to said phonograph, loud speaker and amplifying horn and comprising a revoluble member having a pasageway therein adapted to connect said amplifying horn with either said phonograph or said loud speaker, a pinion mounted on said member and rotating therewith, an operating rod having a pinion meshing with said first named pinion, and means for rotating said rod.

6. In combination, a phonograph, a loud speaker, an amplifying horn, a valve having three legs connected respectively to said phonograph, loud speaker and amplifying horn and comprising a revoluble member having a passageway therein adapted to connect said amplifying horn with either said phonograph or said loud speaker, a pinion mounted on said member and rotating therewith, an operating rod having a pinion meshing with said first named pinion, and means for rotating said rod connected thereto by a universal joint.

7. In combination, a phonograph, a loud speaker, an amplifying horn, a valve having three legs connected respectively to said phonograph, loud speaker and amplifying horn and comprising a revoluble member having

a passageway therein adapted to connect said amplifying horn with either said phonograph or said loud speaker, a pinion mounted on said member and rotating therewith, an operating rod having a pinion meshing with said first named pinion, a cabinet containing said phonograph, loud speaker, and horn, and a knob mounted on the exterior of said cabinet and connected to said operating rod.

8. In a device of the class described, a valve comprising three legs, means for connecting said legs to a phonograph, a loud speaker and an amplifying horn respectively, said valve having a cylindrical opening therein, a cylindrical member revolving in said opening and having a passageway adapted to connect said horn with either said phonograph or said loud speaker, a pinion secured to said member, a bracket loosely supported by said member, an operating rod supported by said bracket and carrying a pinion meshing with said first named pinion, and means for operating said rod.

9. In a device of the class described, a phonograph, a radio loud speaker, an amplifying horn, means comprising a casing connected independently to said phonograph, loud speaker and horn, a valve mounted transversely in said casing and having a passage to connect the horn with the phonograph or with the loud speaker, a pinion fixed to said valve, a rod, a pinion on said rod and meshing with said first named pinion for revolvably operating said valve.

MARTIN NYSTROM.
